United States Patent Office

Des. 179,478
Patented Jan. 1, 1957

179,478

CROWN CATCHER

Clare E. Hodgman, Mamaroneck, N. Y., assignor to The Coca-Cola Company, New York, N. Y., a corporation of Delaware

Application January 10, 1956, Serial No. 39,688

Term of patent 14 years

(Cl. D67—3)

Fig. 1 is a view in perspective of a crown catcher showing my new design;

Fig. 2 is a front view thereof;

Fig. 3 is a vertical sectional view of the instant crown catcher taken along the line 3—3 of Fig. 2, looking in the direction of the arrows;

Fig. 4 is a rear view of said device; and

Fig. 5 is a horizontal cross-sectional view thereof taken along the line 5—5 of Fig. 2, likewise looking in the direction of the arrows.

I claim:
The ornamental design for a crown catcher, as shown.
